US00D992579S

(12) **United States Design Patent** (10) Patent No.: **US D992,579 S**
Ceniceroz (45) Date of Patent: **** Jul. 18, 2023**

(54) **DISPLAY SCREEN OR PORTION THEREOF WITH A GRAPHICAL USER INTERFACE**

(71) Applicant: **IGT**, Las Vegas, NV (US)

(72) Inventor: **David Ceniceroz**, Reno, NV (US)

(73) Assignee: **IGT**, Las Vegas, NV (US)

(**) Term: **15 Years**

(21) Appl. No.: **29/866,424**

(22) Filed: **Sep. 12, 2022**

Related U.S. Application Data

(62) Division of application No. 29/743,414, filed on Jul. 21, 2020, now Pat. No. Des. 966,330.
